(57) **CLAIM**

The ornamental design for a removable battery terminal connector, as shown and described.

DESCRIPTION

FIG. 1 is a pictorial view of a removable battery terminal connector showing our new design.

FIG. 2 presents a front elevational view of the battery terminal connector shown in FIG. 1.

FIG. 3 presents a rear view of the battery terminal connector shown in FIG. 1.

FIG. 4 presents a top plan view of the battery terminal connector shown in FIG. 1.

FIG. 5 is a bottom view of the battery terminal connector shown in FIG. 1.

FIG. 6 presents a right side elevational view of the battery terminal connector shown in FIG. 1; and,

FIG. 7 presents a left side elevational view of the battery terminal connector shown in FIG. 1.

The broken lines in the drawings are for illustrative purposes only and form no part of the claimed design.
